Primary Examiner — T Chase Nelson*Assistant Examiner* — Jonathan J. Han(74) *Attorney, Agent, or Firm* — Banner & Witcoff, Ltd.(57) **CLAIM**

The ornamental design for a shoe, as shown and described.

DESCRIPTION

FIG. 1 is a bottom view of a shoe showing my new design;
 FIG. 2 is a bottom rear perspective thereof; and,
 FIG. 3 is a bottom front perspective view thereof.

The broken lines depicting the remainder of the shoe show
 features that form no part of the claimed design.

1 Claim, 3 Drawing Sheets(56)
